CLAIM

The ornamental design for a lug block of a line stab unit, as shown and described.

DESCRIPTION

U.S. Design application Ser. No. 29/485,773, which is also a continuation of U.S. patent application Ser. No. 14/049,925 is also incorporated herein by reference.

FIG. 1 is a front perspective view of a lug block of a line stab unit showing our new design;

FIG. 2 is a left side view thereof;

FIG. 3 is a right side view thereof;

FIG. 4 is front view thereof;

FIG. 5 is a back view thereof;

FIG. 6 is a top plan view thereof; and,

FIG. 7 is a bottom plan view thereof.
